(57) **CLAIM**

We claim the ornamental design for a battery for portable computer, as shown and described.

DESCRIPTION

FIG. 1 is a front-right-bottom perspective view of a battery for portable computer of the present invention;

FIG. 2 is a front-right-top perspective view thereof;

FIG. 3 is a rear-left-top perspective view thereof;

FIG. 4 is a rear-left-bottom perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken line showing of battery for portable computer is included for the purpose of illustrating environment and forms no part of the claimed design. Additionally, the unevenly broken lines in the drawings define the limits of the claimed design.
